[57] ABSTRACT

A control system for gaseous-discharge tubes which operates upon the hysteresis characteristic of a gaseous-discharge tube. A voltage V_1 is normally applied to one electrode of the gaseous-discharge tube, whereas two voltages V_2 and V_3 are applied to the other electrode through a resistor and a diode respectively. The gaseous-discharge tube is turned on only when the junctions at which said voltages V_2 and V_3 are impressed, are grounded in response to the driving pulses. The gaseous-discharge tube remains turned on even after the driving pulses have disappeared.

GASEOUS-DISCHARGE TUBE CONTROL SYSTEM
BACKGROUND AND SUMMARY OF THE
INVENTION:

The present invention relates to a control system for gaseous-discharge tubes, and more particularly an ON-OFF control system for an array of gaseous-discharge tubes such as neon glow lamps used as a display device for an electronic computer, an analyzer or the like.

In general, electronic computers, analyzers or the like are provided with display devices for representing the processed data for immediate use. Various display elements such as gaseous-discharge tubes, photodiodes, liquid crystal, EL (electric luminescence) elements, cathode ray tubes and the like are widely used, but the gaseous-discharge tubes such as neon glow lamps find a wide application because their operation is stable and dependable and the cost is low.

In general, a gaseous-discharge tube is fired or turned on at a starting voltage different from a voltage at which the gaseous-discharge tube is extinguished or turned off. The starting voltage or turn-on voltage V_a is higher than the turn-off voltage V_b . Therefore, when a pulse voltage which is higher than the difference between the starting voltage V_a and a bias voltage V_c intermediate the voltages V_a and V_b normally impressed to a gaseous-discharge tube is impressed or superposed upon the bias voltage V_c , the gaseous-discharge tube is immediately turned on, and remains turned on even after the pulse voltage has disappeared. To turn off the gaseous-discharge tube, a negative pulse voltage which is less than the difference between the bias voltage V_c and the turn-off voltage V_b may be applied only for a very short time.

In the discharge-tube display devices, a large number of gaseous-discharge tubes such as neon glow lamps are arrayed in rows and columns. To operate the gaseous-discharge tube display device, there has been used a control system which works on the hysteresis characteristic of the gaseous-discharge tubes used for statically controlling the ON-OFF controls of selected gaseous-discharge tubes. That is, each of the gaseous-discharge tubes arrayed in rows and columns is impressed with a bias voltage V_c , and the driving pulses are impressed or superimposed on the bias voltage V_c of a selected gaseous-discharge tube through a row and column driving circuits external of the array of gaseous-discharge tubes so that the sum of the bias voltage V_c and the pulse voltages may be over the starting or turn-on voltage V_a . As a result, the selected gaseous-discharge tube is turned on, and remains turned on even after the pulse voltages have disappeared.

However, in the control system of the type described, the pulse driving voltages are also impressed on all gaseous-discharge tubes in the selected row and column so that they tend to be turned on very often. To overcome this problem, there has been proposed a control system in which each gaseous-discharge tube is provided with an AND circuit which outputs the signal only when the row and column driving pulse voltages are simultaneously applied so that in response to the output signal from the AND gate, only the selected gaseous-discharge tube may be turned on. In this control system, the AND gates will not output the signals when only the row or column driving pulse voltage is applied so that the erratic operation resulting when gaseous-discharge tubes that are not selected are fired

may be prevented. However, this control system is very complex in circuitry, with a large number of circuit component parts.

One of the objects of the present invention is therefore to provide a control system for a gaseous-discharge tube which may ensure reliable and dependable operation and may prevent erratic operation.

Another object of the present invention is to provide a control system for an array of gaseous-discharge tubes in which each gaseous-discharge tube is provided with a special AND circuit designed in accordance with the present invention so that a reduction in the number of circuit component parts may be attained.

Briefly stated, according to the present invention, 15 one electrode of the gaseous-discharge tube is connected to a first power source, whereas the other electrode is grounded through a series circuit comprising a current limiting resistor and a first resistor. The junction between the current limiting resistor and the first transistor is connected to a second power source, and the junction between the other electrode of the gaseous-discharge tube and the current limiting resistor is connected through a diode to a third power source which in turn is grounded through a second transistor. 25 When both the first and second transistors are cut off, the voltage which equals the difference between the voltages of the first and second power sources is impressed to the gaseous-discharge tube so that the latter remains turned off. However, when both the first and second transistors are conducting, the voltage impressed to the gaseous-discharge tube rises to the voltage of the first power source so that the gaseous-discharge tube is turned on. Once the gaseous-discharge tube is turned on, it remains turned on even after the first and second transistors are both cut off.

The above and other objects, features and advantages of the present invention will become more apparent from the following description of the preferred embodiment thereof taken in conjunction with the accompanying drawing.

BRIEF DESCRIPTION OF THE DRAWING

FIG. 1 is a graph of the voltage-current characteristic curve of a gaseous-discharge tube for explanation of the hysteresis characteristic thereof;

FIG. 2 is a circuit diagram of one prior art ON-OFF control system for gaseous-discharge tubes;

FIG. 3 is a circuit diagram used for explanation of the underlying principle of the present invention; and

FIG. 4 is a circuit diagram of a control system for an array of gaseous-discharge tubes in accordance with the present invention.

DESCRIPTION OF THE PREFERRED EMBODIMENT

FIG. 1 shows the voltage-current characteristic curve of a typical gaseous-discharge tube (to be referred to as a "discharge tube" for brevity in this specification). The voltage applied to the discharge tube is plotted along the abscissa whereas the current flows through the discharge tube along the ordinate. It is seen that the starting voltage or turn-on voltage V_a is different from the turn-off voltage V_b . That is $V_a > V_b$. Therefore, when the bias voltage V_c intermediate the turn-on and turn-off voltages V_a and V_b is normally impressed to the discharge tube, the latter will be immediately turned on when a pulse voltage which is equal to the difference

between the starting voltage V_a and the bias voltage V_c is superposed upon the bias voltage V_c . Once the discharge tube is turned on, it remains glowing even if the pulse voltage is removed. In like manner, when the negative pulse voltage which equals the difference between the bias voltage V_c and the turn-off voltage V_b is impressed, the discharge tube may be immediately turned off.

When the hysteresis characteristic of the discharge tube described above is utilized, one or any number of plurality of discharge tubes may be selectively turned on or turned off.

Next referring to FIG. 2, the prior art display device will be described briefly in order to clearly point out the problems encountered in the prior art device. The display device is shown as comprising a 2×2 array of the discharge tubes T_{11} , T_{12} , T_{21} and T_{22} , but it should be understood that in practice a large number of discharge tubes are used. One electrode of the discharge tube T_{11} is connected to a first d-c power source V_{11} whereas the other electrode is grounded through a current limiting resistor R_{11} and a transistor Tr_{11} . The junction between the current limiting resistor R_{11} and the transistor Tr_{11} is connected through a resistor to a second d-c power source V_{21} . To the base of the transistor Tr_{11} is connected an AND circuit comprising diodes D_{11} , D_{11}' and D_{11}'' . To the junction a between the diodes D_{11} and D_{11}' is impressed through a resistor a positive voltage V_{31} . The instantaneous positive pulse signals P_1 and Q_1 are applied to the diodes D_{11} and D_{11}' . Other discharge tubes T_{12} , T_{21} and T_{22} are connected in a similar manner to that described above. The voltage V_{11} of the first d-c power source is the starting or turn-on voltage V_a , and the difference between the voltages V_{11} and V_{21} of the first and second d-c power sources is the bias voltage V_c .

When the pulse signals P_1 and Q_1 are both absent, the potential at the junction a is almost zero so that the transistor Tr_{11} remains cut off. As a result, the bias voltage ($V_{11} - V_{21}$) is impressed to the discharge tube T_{11} so that the latter remains turned off. When either of the pulse signal P_1 or Q_1 is applied to the diode D_{11} or D_{11}' , the potential at the junction a is still zero so that the transistor Tr_{11} still remains cut off. As a result, the discharge lamp T_{11} still remains turned off. When both the pulse signals P_1 and Q_1 are applied to the diodes D_{11} and D_{11}' , the potential at the junction a rises to V_{31} which is applied through the diode D_{11}'' to the base of the transistor Tr_{11} so that the latter is conducted. As a result, the voltage impressed to the discharge tube T_{11} rises to the voltage V_{11} of the first d-c power source, that is the starting voltage V_a so that the discharge tube T_{11} is now turned on. Even if both the pulse signals P_1 and Q_1 disappear so that the transistor Tr_{11} is cut off, the discharge tube T_{11} remains turned on. The other discharge tubes T_{12} , T_{21} and T_{22} are turned on in a manner similar to that described above.

The diode D_{11}'' is inserted in order to prevent the transistor Tr_{11} from conducting in response only to either of the pulse signals P_1 or Q_1 so that this diode D_{11}'' cannot be eliminated in the prior art device. As a result, each discharge tube unit requires three diodes and one transistor so that the circuitry becomes complex in construction and expensive in cost with the increased number of circuit component parts.

THE PRESENT INVENTION

Next referring to FIG. 3, the underlying principle of the present invention will be described. One electrode of the discharge tube T is connected to the power source with the voltage V_1 whereas the other electrode, that is the junction c is grounded through a current limiting resistor R_{01} and a transistor Tr_1 . The junction d between the resistor R_{01} and the transistor Tr_1 is applied with the voltage V_2 through a resistor R_{02} , and the junction c between the discharge tube T and the resistor R_{01} is applied with the voltage V_3 through a diode D and a resistor R_{03} , the junction e between which is grounded through a transistor Tr_2 . To the bases of the transistors Tr_1 and Tr_2 are applied the instantaneous pulse signals P and Q , respectively so that the transistors Tr_1 and Tr_2 are conducted or ON. The magnitudes of the voltages V_1 , V_2 and V_3 are so selected as to satisfy the following condition:

$$V_1 > V_a > V_1 - V_2 > V_b$$

$$V_1 > V_a > V_1 - V_3 > V_b$$

where

V_a = starting or turn-on voltage; and

V_b = turn-off voltage. More preferably the voltages V_2 and V_3 are so selected that when the discharge tube T is turned off, the potential at the junction c equals the voltage V_2 . When both the transistors Tr_1 and Tr_2 are cut off, the potential at the junction c is given by the following relation:

$$\text{Potential at } c = V_2 + (R_{01} + R_{02})/(R_{03} + R_d + R_{01} + R_{02}) (V_3 - V_2) \quad (1)$$

where R_d = internal resistance of diode D . It is seen that in order that the second term of Eq. (1) may become zero,

$$V_2 = V_3 \quad (2)$$

when the transistor Tr_1 is conducted whereas the transistor Tr_2 is cut off, the potential at the junction c is given by

$$\text{Potential at } c = (R_{01})/(R_{03} + R_d + R_{01}) V_3 \quad (3)$$

Since it is preferable that the potential at the junction c equals the voltage V_2 , the following relation must be satisfied:

$$R_{01}/(R_{03} + R_d + R_{01}) V_3 = V_2 \quad (4)$$

From Eqs. (2) and (4), the voltages V_2 and V_3 must be ideally so selected as to satisfy the following relation:

$$V_2 \leq V_3 \leq (R_{03} + R_d + R_{01})/R_{01} V_2 \quad (5)$$

When the voltages V_2 and V_3 will not satisfy Eq. (5), the bias voltage impressed to the discharge tube T is decreased so that the erratic operation tends to occur very often.

When the transistors Tr_1 and Tr_2 are both cut off, the potential at the junction c equals the voltage V_2 so that

the voltage ($V_1 - V_2$) is impressed to the discharge tube T. As a result, the discharge tube T remains turned off. When the transistor Tr_2 is conducting whereas the transistor Tr_2 is cut off, the potential at the junction e lowers to the earth potential, but the potential at the junction c remains at the level of the voltage V_2 because the current which flows from the power source V_2 through the resistor R_{02} and R_{01} to the junction e is interrupted by the diode D. As a result, the discharge tube T remains turned off.

Next when the transistor Tr_1 is conducting and the transistor Tr_2 is cut off, the potential at the junction d is at the earth potential so that the current from the power source with the voltage V_3 flows into the transistor Tr_1 through the resistor R_{03} , the diode D and the resistor R_{01} . In this case, the potential at the junction c is given by Eq. (3), and the voltage equal to $V_1 - R_{01}/(R_{03} + R_d + R_{01}) V_3$ is impressed to the discharge tube T. However, the current limiting resistor R_{01} is relatively very high so that $R_{01} > R_{03} + R_d$. Therefore, the voltage impressed to the discharge tube T is slightly higher than the voltage ($V_1 - V_3$) so that the discharge tube T remains turned off.

Next when the transistors Tr_1 and Tr_2 are both conducting in response to the pulse signals, the potentials at the junctions c and d are equal to the earth voltage so that the voltage V_1 is impressed to the discharge tube T. As a result, the discharge tube T is turned on. Once the discharge tube T is turned on, it remains turned on even when the transistors Tr_1 and Tr_2 are both cut off because the voltage ($V_1 - V_3$) is impressed to the discharge tube T.

In summary, according to the present invention, only when the pulse signals P and Q are simultaneously applied to the transistors Tr_1 and Tr_2 so that the latter are caused to conduct simultaneously, the discharge tube T is turned on. However, when only one of the signal pulses P and Q is applied, the discharge tube T will not turn on.

In FIG. 4, the embodiment of the present invention is shown as comprising a 2×2 array of discharge tubes T_{11} , T_{12} , T_{21} and T_{22} , but it should be understood that in practice a large number of discharge tubes are arrayed. Since the circuit arrangements of the four discharge tube units are substantially similar it will suffice to describe only one unit T_{11} . The voltage V_{11} is impressed to one electrode of the discharge tube T_{11} , and the other electrode is grounded through the resistor R_{11} and the transistor Tr_{11} . The voltage V_{31} is impressed through the resistor R, and the diode D_{11} to one end of the resistor R_{11} , and the voltage V_{21} is impressed through the resistor R_{10} to the other end of the resistor R_{11} . The junction between the resistor R_{11} and the diode D_{11} is grounded through the transistor Tr_{21} . It should be noted that the transistor Tr_{11} is common to the discharge tubes T_{11} and T_{12} , whereas the transistor Tr_{12} , common to the discharge tubes T_{21} and T_{22} . Similarly, the transistor Tr_{21} is common to the discharge tubes T_{11} and T_{21} whereas the transistor Tr_{22} , common to the discharge tubes T_{12} and T_{22} . That is, only one transistor is provided for the discharge tubes in each row and column, and only one diode D is provided for each discharge tube.

The voltages and circuit component parts shown in FIG. 4 correspond to those shown in FIG. 3 in the following manner. That is, the voltage V_{11} , V_{21} and V_{31} correspond to the voltage V_1 , V_2 and V_3 , respectively;

the resistors R_{11} , R_{10} and R_1 , to the resistors R_{01} , R_{02} and R_{03} , respectively; the transistors Tr_{11} and Tr_{21} , to the transistors Tr_1 and Tr_2 , respectively; and the diode D, to the diode D. The voltages V_{11} , V_{21} and V_{31} are selected to satisfy the relations described with reference to FIG. 3.

When the pulse signals P_1 and Q_1 (corresponding to the pulse signals P and Q in FIG. 3) are applied to the bases of the transistors Tr_{11} and Tr_{21} , respectively, the latter are caused to conduct so that the discharge tube T_{11} is turned on. In like manner, only when the pulse signals P_1 and Q_2 are applied simultaneously, the discharge tube T_{12} is turned on. Only when the pulse signals P_2 and Q_1 are applied simultaneously, the discharge tube T_{21} is turned on. Only when the pulse signals P_2 and Q_2 are simultaneously applied, the discharge tube T_{22} is turned on. Once the discharge tube is turned on, it remains turned on even after the pulse signals P and Q have disappeared. To turn off the discharge tube T_{11} , the impression of the voltage V_{11} is ceased.

What is claimed is:

1. A control system for a gaseous-discharge tube comprising

- a gaseous-discharge tube having two electrodes,
- means for impressing a voltage V_1 to one electrode of said gaseous-discharge tube,
- means for impressing a voltage V_2 to the other electrode of said gaseous-discharge tube through a resistor,
- means for impressing a voltage V_3 to said other electrode of said gaseous-discharge tube through a diode, and
- means for grounding the points at which said voltages V_2 and V_3 are applied only when a selected pair of driving pulses are applied to the means for grounding, said voltages V_1 , V_2 , and V_3 satisfying the following relation

$$V_1 > V_a > V_1 - V_2 > V_b$$

$$V_1 > V_a > V_1 - V_3 > V_b$$

where V_a = starting or turn-on voltage of the gaseous discharge tube, and V_b = turn-off voltage of the gaseous discharge tube.

2. A control system for a gaseous-discharge tube as set forth in claim 1 wherein said point at which said voltage V_2 is applied is grounded through a first switching element which in turn is driven by a first driving pulse and whose state is reversed in response to said first driving pulse; said point at which said voltage V_3 is applied is grounded through a second switching element which in turn is driven by a second driving pulse, whereby only when said first and second pulses are simultaneously applied to said first and second switching elements said voltage application points are grounded to thereby turn on the gaseous-discharge tube.

3. A control system for an array of a plurality of gaseous-discharge tubes comprising

- a plurality of gaseous-discharge tubes arrayed in rows and columns,
- means for impressing a voltage V_1 to one electrode of each of said plurality of gaseous-discharge tubes,
- means for impressing a voltage V_2 to the other electrode of each gaseous-discharge tube through a resistor,

- d. means for impressing a voltage V_3 to the other electrode of each gaseous-discharge tube through a diode,
- e. means for grounding all points in one row at which said voltage V_2 is applied only when a row driving pulse is applied to said one row, and
- f. means for grounding all points in one column at which said voltage V_3 is applied only when a column driving pulse is applied to said one column, said voltages V_1 , V_2 and V_3 satisfying the following

relation:

$$V_1 > V_a > V_1 - V_2 > V_b$$

$$V_1 > V_a > V_1 - V_3 > V_b$$

where

 V_a = starting or turn-on voltage, and V_b = turn-off voltage.
